Primary Examiner — Philip S Hyder*Assistant Examiner* — Sydney R Buffalow(57) **CLAIM**

I claim the ornamental design for a shelving cross member, as shown and described.

DESCRIPTION

FIG. 1 is a perspective front left side top view of the shelving cross member.

FIG. 2 is a front elevation view thereof.

FIG. 3 is a left side elevation view thereof.

FIG. 4 is a top plan view thereof.

FIG. 5 is a right side elevation view thereof.

FIG. 6 is a back elevation view thereof.

FIG. 7 is a bottom plan view thereof; and,

FIG. 8 is a perspective top right side back view of shelving cross member in use.

The broken lines shown in the drawings are directed to environment, and are for informational purposes only and form no part of the claimed design.
